CARD PRESS

Arthur E. Mortimer and John Sampson Francis,
Los Angeles, Calif.; said Mortimer assignor to
said Francis

Application March 4, 1939, Serial No. 259,854

2 Claims. (Cl. 100—57)

Our invention relates to a card press and has for its principal object, the provision of a relatively simple, practical and inexpensive device that may be conveniently employed for receiving and holding under pressure, one or more decks of playing cards and the use of which card press adds materially to the life or periods of service of the decks of cards that are contained in the press while not in use.

Further objects of our invention are, to provide a card press that is compact in structure, capable of being readily manipulated to permit the insertion and removal of the decks of cards and further, to provide a card press wherein the developed pressure is uniformly distributed throughout all of the decks of cards that are positioned in the press.

With the foregoing and other objects in view, our invention consists in certain novel features of construction and arrangement of parts that will be hereinafter more fully described and claimed and illustrated in the accompanying drawings in which:

Fig. 1 is a perspective view of a card press constructed in accordance with our invention.

Fig. 2 is a vertical longitudinal section taken approximately on the line 2—2 of Fig. 1.

Fig. 3 is a cross section taken on the line 3—3 of Fig. 2.

Fig. 4 is a cross section taken on the line 4—4 of Fig. 2.

Fig. 5 is a detail section taken on the line 5—5 of Fig. 3.

Fig. 6 is a perspective view looking against the rear side of the card press.

Fig. 7 is a perspective view of one end of the main frame of the card press.

Referring by numerals to the accompanying drawings, 10 and 11 designate the end walls or panels of the press, which walls are preferably rectangular in form and have dimensions slightly greater than the dimensions of the conventional playing cards. These end walls may be made from any suitable material, but in order to add to the appearance of the press we prefer to form these end walls from hardened plastic material which may be colored and finished as desired.

End wall 10 is provided on its inner face with a recess 12 and projecting from the body of the wall into said recess are studs 13 disposed one above the other. The other end wall or panel 11 is provided on its inner face with a recess 14 and formed in the center of said wall or panel 11 is a circular aperture 15.

A substantially rectangular skeleton frame, preferably formed of sheet metal, is disposed between the end walls 10 and 11 with the ends of said frame positioned in the recesses 12 and 14. This skeleton includes a bottom plate 16 formed from suitable sheet metal and provided with lon-

gitudinally disposed ribs 17 in order to increase its stiffness and rigidity. A similar plate 18 provided with longitudinally disposed reinforcing ribs 19 forms the upper member of the skeleton frame and secured to and projecting upwardly from the central portion of the upper plate 18 is a handle 20 which may be of any desired size and configuration.

The ends of the plates 16 and 18 that occupy 10 the recess 12 in end wall 10 are secured in any suitable manner to flanges 21 that are formed on the upper and lower edges of an end plate 22, the latter being preferably formed from suitable sheet metal and provided on its vertical edges 15 with flanges 23.

In order to simplify the connections of the ends 20 of plates 16 and 18 to the end plate 22, ears 24 are struck from the material forming the top and bottom plates at the ends thereof and these ears 25 are inserted through corresponding apertures 25 that are formed in the flanges 21 and the ends of said ears that project through said apertures are pressed downwardly against the surfaces of the flanges, thus providing strong and rigid connections without involving the use of screws, rivets and the like. Plate 22 is rigidly secured 25 to end wall 10 by means of screws 26 that pass through said plate into the studs 13.

The ends of the plates 16 and 18 opposite the 30 ends that are connected to plate 22 are rigidly connected to the upper and lower ends of a metal plate 27 that is dished both vertically and horizontally so as to provide a low or flat pyramid or cone that projects inwardly or toward the plate 35 22.

The vertical and horizontal edges of this dished 40 plate 27 are provided with integral flanges 28 and formed therein are apertures 29, similar to the apertures 25 and which receive ears 30 similar to ears 24 and which are struck from the ends of plates 16 and 18 that overlie the upper and lower flanges of the dished plate.

The space between the top and bottom plates 18 and 16 is adapted to receive the packs of 45 cards C that are placed in the press and said packs are separated by plates 31, preferably formed from hardened plastic material, hard wood or the like and having practically the same length and width as a standard playing card. In 50 order to support the inserted packs of cards and separator plates 31, a pair of spaced horizontally disposed rails 32 are arranged between the end plates 22 and 27 on the rear side of the press, the ends of said rails extending through slots 33 55 that are formed in said plates 22 and 27 and those portions of said rails that project through said plates bear against the adjacent side flanges 23 and 28 (see Figs. 3 and 7).

Disposed within the press just inside the dished 60 plate 27 is a pressure plate or block 34 in the

outer face of which is formed a recess 35. This pressure block is preferably formed of hardened plastic material and positioned in the recess 35 in said block is a plate 36, preferably of sheet metal, provided on its edges with flanges 37 that bear on the side and end faces of the recess 35. A plate 38, preferably of sheet metal, provides a closure for the recess 35 and said cover plate is secured to lugs 39 that project into the recess from the body of the pressure plate 34 by means of screws 40. Formed in the central portion of plate 36 is a depression 41 that receives the head 42 of a screw 43, which latter projects outwardly through an opening 44 in cover plate 38 and said screw also passes through a threaded aperture 45 that is formed in the apex of the dished plate 27.

Mounted on the outer end of screw 43 is a block 46, either square or non-circular in cross section, and said block is arranged for sliding movement in a square or non-circular metal tube 47. This tube is embedded in the shank portion 48 of an operating handle 49 and secured on the shank 48, preferably by being pressed thereupon, is a metal sleeve 50, the inner end of which is flanged outwardly as designated by 30a against a flange that is formed integral with the inner face of end wall or plate 11 around the opening 15 therein.

Opening 15 provides a bearing for the shank portion 48 of the handle and the sleeve 50 that is carried thereby and the inner ends of the tube 47 and shank 48 that project a short distance inwardly from the flange 30a bear against a thrust washer 51 that is positioned against the central portion of the convex face of the dished plate 27.

Dished plate 27 is suitably secured to the end wall or plate 11, preferably by means of screws that pass through said dished plate and enter lugs that are formed integral with the inner face of plate 11 and which structure is somewhat similar to the screws 26 that enter lugs 13 for the purpose of securing plate 22 to the end wall or plate 10.

A dished plate 27 provides a housing that covers the thrust washer 51 and the inner end portions of shank 48, sleeve 50 and tube 47.

The head 42 of screw 43 is provided with a convex outer face which bears in the concave depression 41 and such structure provides a universal joint connection between the inner end of screw 43 and pressure plate 34 so that the latter may swing freely for a limited distance in all directions and, therefore said plate is self-adjusting with respect to the cards that are placed in the press.

As a result of the construction just described, the handle 49, its shank 48 and sleeve 50 may be rotated in the bearing provided by the aperture 15 and the flange surrounding same and as the block 46 on the outer end of screw 43 engages in the square or non-circular tube 47, said block and screw will be rotated and at the same time they will move longitudinally relative to the operating handle, by reason of the fact that the screw 43 has threaded engagement with the center or apex of the dished plate 27. Thus, when handle 49 is manipulated so as to move the screw 43 inwardly, the head carried by the inner end of said screw will bear on plate 36 to move the same and pressure plate 34 inwardly, thereby exerting pressure on the packs of cards that are positioned in the press and which are separated by the plates 31.

Thus, a plurality of packs of cards may be placed in the press and maintained under pressure while not in use and, as a result, the life or period of service of the cards will be greatly increased as compared to cards that are not subjected to pressure while not in use.

It will be understood that when the handle 49, its shank 48 and sleeve 50 are manipulated, said parts rotate in the bearing formed by the aperture 15 and the flange surrounding the same without moving longitudinally.

Plate 27 is dished in order to produce sufficient stiffness and rigidity to resist and distribute evenly the strains and stresses that are imparted to said plate and the frame of which said plate is a part, while the screw is being moved inwardly to apply pressure to the packs of cards positioned in the device between the separator plates 31.

Thus it will be seen that we have produced a card press that is relatively simple in construction, inexpensive of manufacture and very effective in performing the functions for which it is intended.

It will be understood that minor changes in the size, form and construction of the various parts of our improved card press, may be made and substituted for those herein shown and described, without departing from the spirit of our invention, the scope of which is set forth in the appended claims.

We claim as our invention:

1. In a card press, the combination with an integral frame comprising a top plate, a handle secured to the central portion of said top plate, a bottom plate, a pair of end plates, a pair of rails connecting said end plates on one side of the frame, the opposite side of the frame being open, one of which end plates is dished inwardly, of a pressure plate arranged for movement within said frame adjacent said dished plate, a reinforcing plate embedded in said pressure plate, which reinforcing plate is dished toward said dished end plate, a cover plate applied to the end of the frame over said dished plate, a member mounted for rotation in said cover plate, a screw passing through said dished end plate, the outer portion of which screw has sliding engagement with the member that is mounted for rotation and the inner end of which screw bears against the central portion of the dished reinforcing plate in said pressure plate.

2. In a card press, the combination with an integral frame comprising a top plate, a handle secured to the central portion of said top plate, a bottom plate, a pair of end plates, a pair of rails connecting said end plates on one side of the frame, the opposite side of the frame being open, one of which end plates is dished inwardly, of a pressure plate arranged for movement within said frame adjacent said dished plate, a reinforcing plate embedded in said pressure plate, which reinforcing plate is dished toward said dished end plate, a cover plate applied to the end of the frame over said dished plate, a member mounted for rotation in said cover plate, a screw passing through said dished end plate, the outer portion of which screw has sliding engagement with the member that is mounted for rotation and a universal joint between the inner end of said screw and the central portion of the dished reinforcing plate in said pressure plate.

ARTHUR E. MORTIMER.
JOHN SAMPSON FRANCIS.
